UNITED STATES PATENT OFFICE.

AUGUST A. RUSTEBERG, OF CHICAGO, ILLINOIS.

OIL-GAS GENERATOR AND BURNER.

1,273,277.

Specification of Letters Patent. Patented July 23, 1918.

Application filed June 9, 1917. Serial No. 173,737.

To all whom it may concern:

Be it known that I, AUGUST A. RUSTEBERG, a citizen of the United States, and a resident of the city of Chicago, in the 5 county of Cook and State of Illinois, have invented certain new and useful Improvements in Oil-Gas Generators and Burners; and I do hereby declare that the following is a full, clear, and exact description of the 10 same, reference being had to the accompanying drawings, and to the numerals of reference marked thereon, which form a part of this specification.

This invention relates to an improved 15 form of a gas generating oil burner adapted for use in combination with kitchen stoves and ranges, and comprises a primary heating means adapted to originally burn oil to heat kerosene oil to convert the same into 20 a gas by the carburetion of air thereof. Said gas is adapted to be used as a fuel to burn in cooking burners provided for the purpose, and is furthermore used as a fuel in the primary heating means to perpetuate 25 the gas generating process after the same has been started.

It is an object of this invention to construct a gas generating oil burner adapted for use in combination with ordinary coal 30 burning kitchen ranges.

It is also an object of this invention to provide a gas generating burner wherein an oil burning starting burner is used to start the generation of a gas from oil after 35 which the generated gas is mixed with air in suitable chambers and fed to cooking burners to be used as a fuel, and to an auxiliary burner adapted to heat an oil supply mechanism to continue the gas generating 40 process.

It is a further object of this invention to construct an adjustable and portable burner embracing an oil burning starter adapted to heat oil for the generation of a gas which 45 is carbureted with air in suitable chambers provided for the purpose and used as a fuel in cooking burners and in a gas generating burner to heat additional oil to convert the same into a gas to continue the process.

It is furthermore an object of this invention to provide a burner adapted to be removably set within the coal pit of a kitchen stove, and comprising an oil supply mechanism heated by an oil-gas burner to volatilize 50 the oil which passes into suitable mixing chambers and is mixed with air and is

then supplied as a fuel to said oil-gas burner to continue the process of gas generation, and to adjustable cooking burners adapted to fit in the openings of the kitchen stove 60 when the cover plates are removed.

Other and further important objects of the invention will be apparent from the disclosures in the drawings and specification.

The invention (in a preferred form) is 65 illustrated in the drawings and hereinafter more fully described.

On the drawings:

Figure 1 is a front elevation view of an oil-gas generator and burner embodying the 70 principles of this invention.

Fig. 2 is a top plan view thereof showing the adjustability of the cooking burners in dotted lines.

Fig. 3 is an end view of the device.

Fig. 4 is a similar view with the starting heater removed.

Fig. 5 is an enlarged section taken on line 5—5, of Fig. 1, with parts shown in plan.

Fig. 6 is an enlarged section taken on 80 line 6—6, of Fig. 2, with parts omitted.

Fig. 7 is a section taken on line 7—7, of Fig. 6.

Fig. 8 is a section taken on line 8—8, of Fig. 2, with parts omitted and parts broken 85 away.

Fig. 9 is an enlarged section taken on line 9—9, of Fig. 2, with parts omitted.

Fig. 10 is an enlarged longitudinal section taken through the oil vaporizing tube, 90 with parts connected therewith shown in elevation.

Fig. 11 is a top plan view of the bottom plate of the cooking burner shown in Fig. 8.

Fig. 12 is an enlarged section taken on 95 line 12—12, of Fig. 4, with parts shown in elevation and with parts broken away.

Fig. 13 is an inner end view thereof.

Fig. 14 is a vertical section taken through a modified form of cooking burner.

Fig. 15 is a longitudinal section taken through a modified form of carbureting chamber.

As shown in the drawings:

The reference numeral 1, indicates a large 105 casing, storage tank or primary gas reservoir, having an aperture in each end thereof in which is removably threaded a plug 2, to close the same. An aperture 3, is provided in the rear wall of the casing 1, the 110 margin of which is bent outwardly to form a collar 4, in which is removably threaded

a large plug 5, to close the aperture 3. Integrally formed on the front wall of the casing 1, and in communication with the interior thereof, is a small casing or secondary 5 gas reservoir 6, having an aperture 7, in the outer end wall thereof, for a purpose herein-after described. The top of the small casing 6, comprises two parallel grooved sections or troughs 8, spaced from one another to 10 afford a long longitudinal passage or opening 9, therebetween, and each having a wick 10, of any suitable material disposed or seated therein to afford a starting burner when the wicks are saturated with kerosene. 15 Integrally connected to the inner or adjacent walls of the troughs 8, to span the opening 9, are a plurality of parallel crosspieces or bars spaced a short distance apart to form a long narrow grid or generating burner 11, 20 between the troughs 8, forming the starting burner.

An aperture or oil gas opening 12, is formed near each end of the top wall of the casing 1, and integrally formed or rigidly 25 secured around each aperture a short distance from the periphery thereof to afford a shoulder or seat 13, is a ring or collar 14.

A cooking burner is removably mounted over each of the oil-gas openings 12, and 30 comprises a stand or feed pipe 15, the lower end of which is adapted to rotatably and removably fit in one of the collars 14, and seat or rest upon the shoulder 13, thereof. The upper end of each feed pipe 15, is rigidly 35 secured to or expanded into a suitable gas inlet opening provided near the outer periphery of a bottom or base plate 16, having a peripheral notch or groove 17, therein to permit a burner casing 18, to seat upon said 40 base plate, as clearly shown in Fig. 8. The top wall of each burner casing 18, has a plurality of small gas apertures 19, therein. Rigidly secured upon the upper rim of each burner casing are a number of equidistantly 45 spaced arms or supports 20, to hold a baffle plate or stove plate 21, in position above and parallel to the top of each burner casing 18. Each baffle plate is provided with a large 50 central opening 22, surrounded by a plurality of small apertures 23, to permit the oil-gas flames to pass therethrough to heat a cooking utensil placed upon the baffle plate. Pivotaly mounted upon each of the base plates 16, by means of a pin 24, to form 55 a valve is a shutter, regulating or controlling disk 25, provided with a handle 26, which extends outwardly through a suitable slot in the burner casing 18, to afford a means for swinging the disk 25, to regulate 60 the flow of oil-gas from the casing 1, into the cooking burners.

Integrally formed or rigidly secured to the bottom of the casing 1, is a fuel mixing or carbureting pipe 27, the inner end of 65 which is bent or curved upwardly to com-

municate with the interior of said casing through a suitable fuel inlet opening 28, formed in the bottom of the casing. Secured within the mixing pipe 27, is a tube 29, the outer diameter of which is less than 70 the inner diameter of the pipe 27. Integrally formed on each end of the tube 29, are a plurality of lugs 30, which contact the inner surface of the pipe 27, to hold the tube 29, spaced from the pipe 27, and afford a 75 passage 31, between said pipe and tube. Secured over the outer end of the mixing pipe 27, is an air intake elbow 32, having an aperture 33, in the outer curved portion thereof.

Engaged in the aperture 33, is the tapered 80 or inner end of a nozzle 34, having a small longitudinal passage 35, in the inner end thereof which communicates with a large longitudinal threaded passage 36, to afford a valve seat 37, at the point where said passages join. Adjustably threaded in the passage 36, is a threaded shank or screw 38, having integrally formed on one end thereof a valve rod 39, the outer end of which is tapered and adapted to seat in the valve 85 seat 37, to close the oil-gas outlet passage 35, when said valve rod is moved inwardly by the rotation of the screw 38, which may be actuated by a rod 40, integral with the other end of the screw 38. Said rod 40, projects through an apertured cap 41, threaded upon the externally threaded outer end of the nozzle 34, and through the outer wall 42, of an auxiliary wick starting burner 43, and is provided with a handle 44, conveniently 90 located to permit ready adjustment of the oil-gas inlet valve mechanism. Integrally formed or rigidly secured to the outer tapered end of the valve rod 39, and extending through the oil-gas outlet passage 35, is 95 a cleaning blade or knife 45, adapted to be rotated within said passage 35, simultaneously with the actuation of the valve mechanism by the handle 44, to scrape the walls of said passage 35, to keep the same clean from 100 dirt, carbon or other clogging substances.

Integrally formed centrally upon the upper side of the nozzle 34, and at right angles thereto is an inclined generating pipe 46, having a passage 47, therein, the lower end 115 of which communicates with the nozzle passage 36, while the upper end thereof communicates with a passage at right angles thereto formed axially through an externally threaded arm 48, integrally formed 120 on one side of the upper end of the auxiliary oil gas generating pipe 46. Threaded upon the arm 48, is one end of a long slightly inclined main oil-gas generating pipe or tube 49, which extends longitudinally of the device above the generating burner 11, and between the troughs 8, of the starting burner, and is rigidly held in position by supporting brackets 50, secured upon the exterior of the casing 1. Disposed 125

longitudinally within the main generating tube 49, are a plurality of concentric spiral springs or coils 51, which are held therein by means of a passaged coupling or connector, the inner end 52, of which is enlarged and threaded to thread into the open end of the tube 49, while the other end 53, is separated from the enlarged end 52, by a nut 54, and is threaded to receive the end of 10 a kerosene or other hydro-carbon fuel supply pipe or hose thereon.

Threaded into the aperture 7, of the small casing 6, is a threaded passaged arm 55, integrally formed on the inner side of an inclined pipe burner 56, having a plurality of apertures 57, therein. Said pipe burner is disposed parallel to and below the inclined generating pipe 46, to permit oil-gas flames flowing from the apertures 57, to heat 20 the pipe 46, during the process of oil-gas generation.

Rigidly secured below each end of the casing 1, and extending laterally beyond each side thereof is a metal strip or crossbar 58, 25 the ends of which are bent downwardly at right angles to form brackets or arms 59, having a threaded aperture near the lower end to adjustably receive an adjusting bolt 60, threaded therein. Disposed flat against 30 the outside of each of the arms 59, is a standard or leg 61, provided with a vertical slot 62, in the upper portion thereof through which one of the adjusting or locking bolts 60, projects to permit the legs 61, to be adjusted to support the device at different 35 heights.

In the modified form of cooking burner shown in Fig. 14, the numeral 62, designates a stand or feed pipe the upper end of 40 which is expanded into a suitable aperture disposed at one side of the bottom or base plate of the lower section 63, of a burner casing. Mounted upon the rim of the lower section 63, is a partition plate 64, forming a 45 lower chamber 65, and having a large central opening 66, therein over which an externally operated shutter or controlling disk 67, pivotally mounted upon said partition plate 64, is adapted to be moved to regulate 50 the opening from said lower chamber 65, into an upper chamber 68, provided by an upper burner section 69, seated upon the partition plate 64, and having a plurality of burner apertures 70, in the top wall 55 thereof. This arrangement permits the oil-gas mixture entering at the bottom of the lower chamber 65, to pass and expand into said lower chamber and then pass upwardly through the valve opening 66, so that the 60 oil-gas entering the upper chamber 68 may flow out of all of the burner apertures 70, under equal pressure.

In the modified form of carbureting mechanism shown in Fig. 15, the construction of the carbureting or fuel mixing pipe

and the air intake elbow is the same as that disclosed in Fig. 6. The mixing tube 29, however is replaced by a large mixing tube 71, provided with outwardly bent integral lugs 72, to hold the same spaced from contact with the inner surface of the pipe 27, to afford an air passage between the pipe 27, and the tube 71. The inner end of the tube 71, is tapered or restricted to slightly compress the oil-gas passing therethrough so 75 that the oil-gas may expand in the curved end of the pipe 27, and mix with air entering into said pipe from the passage between the pipe and said tube 71. Disposed longitudinally within the tube 71, is a smaller 80 mixing tube 73, provided with integral lugs 74, to hold the same spaced from the inner surface of the tube 71, to afford an air passage between the tube 71 and the tube 73, whereby the air and gas entering the carbureting chambers within the tube 27, formed by the concentric arrangements of the tubes 71 and 73, may be thoroughly 85 mixed before entering the casings 1 and 6.

The operation is as follows:

Kerosene or other suitable hydro-carbon fuel is supplied to the burner through the main generating or supply pipe 49, passing around the spiral concentric springs 51, and into the passage 47. The wicks 10, disposed in the troughs 8, of the primary starting burner, and a wick 75, of the secondary starting burner 43, are saturated with kerosene and lighted, the heat therefrom tending to rapidly heat the pipes 46 and 49, and the 90 springs 51, thus causing a primary generation of oil-gas, in said pipes, which gas passes through the passage 47, into the chamber 36 of the nozzle 34, the tapered end of which projects into the aperture 33, of 95 the air intake elbow 32. By turning the handle 44, the valve rod 39, is unseated permitting the oil-gas to pass through the narrow passage 35. The air flowing into the burner through the open end of the intake 100 elbow 32, flows into the mixing tube 29, with said oil-gas, and through the passage 31, surrounding the tube 29, into the chamber in the curved inner end of the mixing pipe 27, where the air from the passage 31, 115 further mixes with the already partially mixed oil-gas and air flowing from the interior of the mixing tube 29, into the curved portion of said pipe 27. The oil-gas thus thoroughly mixed with air passes upwardly 120 through the opening 28, into the primary fuel gas chamber within the fuel gas reservoir or storage casing 1, and into the secondary fuel gas chamber within the fuel gas storage casing 6.

From the gas chamber within the casing 6, the fuel gas thus generated by the starting burners flows through the slots of the generating burner 11, and out of the apertures 57, of the inclined pipe burner 56, and 130

is ignited thus affording a means for continuing the heating of the gas generating pipes 49 and 46, and the springs 51, to generate more gas by the burning of oil-gas already generated thus permitting the process of oil gas generation to continue, after being started by the starting burners which of course go out after the kerosene with which the wicks are saturated is burned up.

- 10 To utilize the burner as a cooker the fuel gas from the gas chamber within the casing 1, flows upwardly through the pipes 15, and into the interior of the burner casings 18, the shutters having been opened by means of 15 the handles 26. From the casing 18, the gas escapes through the apertures 19, and is ignited, the flames passing through the openings 22, and apertures 23, heating the baffle plates 21, and any cooking utensils which are 20 placed thereon. It will of course be seen that the flow of fuel gas into the cooking burners may be regulated by means of the shutters 25, and that the flow of oil-gas into the mixing chambers of the pipe 27, may be 25 regulated or entirely shut off by turning the handle 44, thus operating the controlling valve within the nozzle 34. The narrow passage 35, of the nozzle 34, is always kept clean from dirt or carbon by means of the 30 knife blade 45, which scrapes the walls of the passage each time the handle 44, is actuated.

When it is desired to shut off the burner the gas valve 39, is closed by turning the 35 handle 44, thus shutting off the gas supply.

The burner is then allowed to burn until the fuel gas supply in the gas chambers is used up.

The plugs 2 and 5, provided to fill the 40 apertures in the casing 1, may be removed at any time to permit additional cooking burners to be attached. It will be noted that the legs 61, for the burner are adjustably mounted to permit the burner to be raised or lowered to fit in an ordinary kitchen coal range 45 or cook stove, with the legs resting upon the coal grate. The cooking burners which are adapted to be rotated in a horizontal plane, may be disposed so that the baffle plates 50 cured thereon will fit in the openings in the top of the range or stove.

The cooking burner shown in Fig. 14, is mounted similar to the cooking burners shown in Fig. 1. The fuel gas entering 55 through the pipe 62, disposed to one side of the burner casing, first enters the lower chamber 65, and then passes upwardly through the central opening 66, when the shutter 67, is open into the upper chamber 68, thus permitting the fuel gas to expand and flow out of all of the apertures 70, under an equal pressure to afford a uniform flame.

In the carbureting or mixing mechanism shown in Fig. 15, the concentric arrangement of the spaced tubes 71 and 73, within

the mixing pipe 27, permits the air and oil gas from the intake elbow 32, and from the gas nozzle 34, to become thoroughly mixed at different points of its passage through said mixing mechanism before passing into 70 the fuel gas chambers of the casings 1 and 6.

I am aware that various details of construction may be varied through a wide range without departing from the principles of this invention, and I therefore do not pur- 75 pose limiting the patent granted otherwise than necessitated by the scope of the appended claims.

I claim as my invention:

1. An oil-gas burner, comprising a primary 80 fuel gas storage casing, a secondary fuel gas storage casing secured thereto, a starting burner thereon, a generating burner also formed upon said secondary casing, an oil supply pipe disposed above said starting 85 burner and said generating burner, said starting burner adapted to be lighted to initially heat the oil supply pipe to start the generation of an oil-gas, mixing mechanisms connected with said primary casing 90 and to said oil supply pipe adapted to mix the generated oil-gas with air before passing into said primary and secondary casings, cooking burners rotatably mounted on said primary casing adapted to receive gas 95 therefrom for cooking purposes, and an inclined generating burner adapted to receive gas from said secondary casing to heat said oil supply pipe to continue the generation of oil-gas.

2. In a burner of the class described, an oil supply pipe, starting burners for initially heating the same to form an oil-gas, means between said starting burners for continuing the generation of oil-gas, air mixing means connected to said supply pipe adapted to mix air with said oil-gas to form a fuel gas, a casing connected with said air mixing means to hold said fuel gas, rotatably adjustable cooking burners on said casing 100 adapted to be fed with fuel gas from said casing for cooking purposes, and auxiliary oil burning means acting to heat said supply pipe to assist in the generation of oil-gas.

3. In a burner of the class described, a 115 storage casing, an oil supply pipe mounted thereon, cooking burners rotatably mounted on said storage casing, concentric coils within said oil supply pipe, starting burners for initially heating said supply pipe and 120 coils to start the generation of oil-gas, means connected with said casing for mixing air with said oil-gas to form a fuel gas adapted to be stored in said casing to supply said cooking burners, a generating burner integral with said starting burners adapted to be supplied with fuel gas from said casing to heat said pipe and coils to continue the 125 generation of oil-gas, and an inclined auxiliary burner connected with said air mixing 130

means to assist in the heating of said supply pipe.

4. In a burner of the class described, storage means, an oil supply pipe supported thereon, an inclined generating pipe connected therewith, adjustable cooking burners mounted upon said storage means, coils disposed within said oil supply pipe, primary starting burners on said storage means on either side of said oil supply pipe to initially heat said pipe and coils to start the generation of oil gas, a secondary starting burner below said inclined generating pipe, mixing means connected with said storage means and with said inclined generating pipe for mixing air with said oil-gas before it enters said storage means, and a generating burner disposed between said primary starting burners adapted to receive mixed oil-gas from said storage means to heat said pipe and coils to continue the generation of oil-gas.

5. In a burner of the class described, a storage tank for gas, cooking burners adjustably mounted thereon supplied with gas therefrom, a fuel supply means supported on said tank, an inclined generating pipe connected therewith, oil burning means acting to initially heat the fuel supply means to generate a gas for storage in said tank, an auxiliary oil burning means acting to heat said inclined generating pipe to assist in the generation of gas, means for mixing air with said gas before entering said tank, and generating burners adapted to be supplied with said gas as a fuel to continue heating said fuel supply means for carrying on the process of gas generation.

6. In an oil gas generator and burner, a gas tank, cooking burners thereon, a main fuel supply pipe, an auxiliary fuel supply pipe connected therewith, a primary oil burner and generating burner below said main supply pipe, and a secondary oil burner and generating burner below said auxiliary fuel supply pipe.

7. In a burner of the class described, a storage tank for gas, cooking burners adjustably mounted thereon supplied with gas therefrom, a fuel supply means supported on said tank, an inclined generating pipe connected therewith, oil burning means acting to initially heat the fuel supply means to generate a gas for storage in said tank, an auxiliary oil burning means acting to heat said inclined generating pipe to assist in the generation of gas, means for mixing air with said gas before entering said tank, generating burners adapted to be supplied with said gas as a fuel to continue heating said fuel supply means for carrying on the process of gas generation, and springs within said fuel supply means adapted to

be heated therewith for facilitating the generation of said gas.

65

8. In an oil-gas burner of the class described, a storage tank for gas, means for adjustably supporting the same at different heights, cooking burners adjustably mounted on said storage tank, a primary kerosene supply member supported on said tank, springs disposed within said primary supply member, an inclined secondary supply member connected with said primary supply member, primary and secondary means for heating said supply member and springs to generate an oil-gas, mixing mechanisms connected with said storage tank, an air intake elbow connected therewith, an adjustable gas inlet means connected with said air intake elbow to supply oil-gas into said mixing mechanisms to be mixed with said air before entering said storage tank, and shutter means in said cooking burners to regulate the supply of gas from said storage tank.

80

9. In an oil-gas burner of the class described adapted to be used in combination with a cook stove, a storage casing for oil-gas, means for adjustably supporting the same within said cook stove, adjustable cooking burners on said casing adapted to be moved through a horizontal plane to fit the holes in the top of the cook stove, an oil supply pipe on said casing, metal springs therein, primary means for heating said pipe and springs to generate an oil-gas adapted to be burned by said cooking burners, an inclined pipe connected with said oil supply pipe, and secondary means below said inclined pipe adapted to burn said generated oil-gas to heat said inclined pipe to continue the process of oil-gas generation.

90

10. In an oil-gas generating burner of the class described, an oil supply pipe, metal coils mounted therein, primary and secondary starting burners to heat said pipe and coils to start the generation of an oil-gas, means associated with said primary starting burners adapted to burn said oil-gas to continue the heating of said pipe and coils to permit the process of oil-gas generation to be carried on indefinitely, and inclined means connected with said supply pipe and disposed above said secondary starting burner to be heated thereby to assist in the oil-gas generating process.

95

110 In testimony whereof I have hereunto subscribed my name in the presence of two subscribing witnesses.
